UNITED STATES PATENT OFFICE.

ROBERT H. LAWSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR RECLAIMING FASTENINGS.

1,403,507.

Specification of Letters Patent. Patented Jan. 17, 1922.

Application filed August 16, 1918. Serial No. 250,153.

To all whom it may concern:

Be it known that I, ROBERT H. LAWSON, a citizen of the United States, residing at Beverly, in the county of Essex and State of Massachusetts, have invented certain Improvements in Machines for Reclaiming Fastenings, of which the following description, in connection with the accompanying drawings, is a specification, like reference 5 characters on the drawings indicating like parts in the several figures.

This invention relates to machines for reclaiming fastenings such, for example, as the metallic fastenings used in the making 15 of shoes, and it has particularly in view the restoration to a condition suitable for use of the tacks which are spilled on the floor in the operation of lasting shoes and are taken up from the floor together with 20 dirt, trash and the like in the sweepings from the lasting room.

In the lasting of McKay shoes tacks of two different lengths are used, relatively short tacks being inserted at the shank of 25 the shoe and longer tacks being inserted at the heel seat and toe portions of the shoe where the stock through which the lasting tacks are driven is of greater thickness than at the shank of the shoe. The 30 operator, commonly, for example, when he lasts first one side of the shoe and then the other at the shank and then, after making the change from shorter to longer fastenings, lasts the toe and the heel seat, with- 35 draws the shoe from the lasting machine several times during the lasting operation in order that he may so manipulate the shoe as to present a different point on the shoe in position to receive the tacks in- 40 serted by the machine. It is not found practicable to stop the operation of the lasting machine while such changes in the presentation of the shoe to the machine are being made, and the continued operation of the 45 machine results in a large number of tacks being discharged on the floor about the machine. It is also common for operators to permit the lasting machines to continue in operation while a change is being made from 50 one shoe to another which, of course, adds to the accumulation of the tacks about the machines. In the manufacture of Goodyear welt shoes also, tacks of different lengths

are used for lasting the heel seat and the forepart and these tacks tend to collect on 55 the floor of the lasting room. Very large quantities of tacks have heretofore been lost in shoe factories in this and other ways since it has been cheaper to purchase new tacks than to employ operatives to pick out the 60 spilled tacks from the trash and dirt with which they become commingled on the floor and to assort them as to length which is necessary to the end that tacks of a certain length may be again introduced into the 65 hopper of the lasting machine designed to receive tacks of such length.

An object of the present invention is to provide mechanism so organized that by its use these tacks may be efficaciously and eco- 70 nomically restored to a condition in which they may be again utilized.

An important feature of the invention resides in the provision of means for separating fastenings from foreign material such 75 as dirt, trash, or the like and then assorting them in accordance with a physical characteristic of the fastenings. With a view to putting into effect the above-mentioned object of the invention the present exemplification of the invention is organized to assort tacks in accordance with their lengths so that tacks of one length may be obtained 80 separate from tacks of a different length.

A second feature of the invention resides 85 in the provision of a machine having a plurality of stations at which are provided means for operating on tacks, such, for example, as mechanism for assorting the tacks in accordance with a physical characteristic 90 of the tacks, and means for distributing the tacks substantially uniformly to said stations.

In the illustrated construction, the means 95 for distributing the tacks uniformly to the various stations comprises a rotary drum having a series of openings arranged spirally of the circumference of the drum through which the tacks pass successively to the various stations.

In accordance with another feature of the invention, means operated in a predetermined path of movement is provided for selecting the tacks in accordance with their lengths, and the tacks are positioned relatively to the path of movement of the select- 105

ing means, by means movable relatively to the path of movement of the selecting means in the direction of the lengths of the tacks so that the selecting means is caused to remove the tacks from the positioning means at points determined by the lengths of the tacks. In the preferred construction, a plurality of assorting stations is provided, and the assorting mechanism 10 comprises members each of which extends in co-operative relation with the assorting stations.

Although the invention will be herein set forth in its application to operating on lasting tacks, it will be understood that the invention as a whole and certain features thereof are capable of use in other applications such, for example, as the reclaiming of other kinds of metallic fastenings, and 20 it is also recognized that the mechanical structure herein illustrated and described may be extensively modified without departing from the principles of the invention.

25 Other objects and features of the invention will appear as the description proceeds.

In the drawings,

Figure 1 is a view in side elevation of a machine according to the invention with 30 parts broken away to show portions of the interior of the machine;

Fig. 2 is a plan view with parts broken away better to exhibit the assorting mechanism of the machine;

35 Fig. 3 is a view in front elevation showing the slide, the picker, and the assorting mechanism at the right hand side of the machine in cross section; and

Fig. 4 is a cross section of the yielding 40 connection for operating the tack carrier.

The machine may be said to comprise generally a plurality of assorting stations 2 having means associated therewith for assorting the tacks in accordance with their 45 lengths and means for separating foreign material such as dirt, trash and the like from the tacks and distributing them to the assorting stations.

The devices for separating the tacks from 50 foreign material and distributing them to the assorting stations comprise a rotary cylindrical magazine 4 having a screened or otherwise reticulated periphery of a mesh small enough to retain the tacks in the magazine but through which fine dust may pass into a receptacle 6 supported on a shelf 8 formed as a part of a bracket 10 extending from the machine frame and providing a bearing 12 in which a hollow boss 14 projecting centrally from one side of the magazine 4 is journaled. A blower (not shown) is connected to the boss 14 for producing a flow of air through the interior of the magazine 4 in order to remove from the magazine 55 any light trash which may be inter-

mingled with the tacks. The magazine 4 is formed with flanges or fins 16 extending radially inwards from its periphery and operating upon rotation being imparted to the magazine to elevate the contents of the magazine and deliver them upon a chute 18. The tacks are introduced into the magazine 4 through a hopper 20 which together with the magazine 4 constitutes a source of tack supply for the machine as a whole.

75 The tacks which, having the fine dust separated therefrom by the screened periphery of the magazine 4 and the light trash removed by pneumatic means through the hollow boss 14, may still have commingled therewith relatively large and heavy pieces of foreign material, are delivered from the chute 18 into the end of a rotary drum 22 which distributes the tacks uniformly to the assorting stations 2. To this end the

80 drum or distributor 22 is provided with openings 24 elongated in the direction of the axis of the drum and arranged spirally of the periphery of the drum. With this construction it is apparent that the tacks 85

can pass from the drum only while one or more of the openings 24 is passing through the lower part of the path of movement of the drum beneath the line of tacks in their advance from the inlet or receiving end of the drum toward its outlet or delivery end.

When, in the continued rotation of the drum, the openings 24 adjacent to the receiving end of the drum have passed from beneath the line of tacks in the drum, a 90

solid or imperforate part of the drum is presented to the tacks near its inlet end in consequence of which they are prevented from passing from the drum until in their 95

advance movement toward the outlet end of the drum they arrive in alignment with other openings 24 which, by reason of the spiral arrangement of the openings in the 100 drum, pass through the lower portion of the path of movement of the drum beneath the line of tacks in the drum at a later period

105 of its rotation than did the openings nearer the receiving end of the drum. The size and arrangement of the openings 24, the speed of rotation of the drum, and the delivery of tacks to the chute 18 by the flanges 110

115 of the magazine 4 may be so regulated as to cause a substantially equal number of tacks to be delivered from the openings 24 of the drum at all points of the drum from its receiving to its delivery end. As shown, the drum 22 is provided with a single row 120

125 only of openings 24 arranged at a relatively high pitch about the periphery of the drum, each of the openings preferably having substantially one half or more of its extent disposed on the side of a plane at right angles to the axis of the drum 22 and passing through the adjacent end of a contiguous opening opposite from said contiguous open-

ing. Referring to Fig. 1, the line A indicates a plane transverse to the axis of the drum 22 and passing through the end of the opening 126 adjacent to the opening 127, 5 and the line B represents a similar plane passing through the end of the opening 125 adjacent to the opening 126. The larger portion of the opening 127 is disposed on the side of the plane A opposite from the 10 opening 126, and, correspondingly, the larger portion of the opening 126 lies on the side of the plane B opposite from the opening 125. By reason of the provision of a single row only of openings 24 arranged as 15 hereinbefore described, the tacks are prevented from escaping too rapidly from the drums 22.

The drum 22 is connected at its ends to disks 26 and 28 journaled in the main frame 20 of the machine. The disks are extended radially beyond the periphery of the rotary drum or distributor 22 and are provided with inwardly projecting flanges 30 and 32 to which is connected for rotation with 25 the drum 22 a screen 34 enclosing the drum. The primary function of the screen 34 is to remove from the tacks which pass therethrough any foreign material which may not have been separated therefrom in the 30 magazine 4 in order that the tacks when delivered to the assorting stations shall be free from foreign material which might interfere with the proper functioning of the assorting mechanism or occasion breakage of 35 some of the parts of the machine. It may be noted, however, that the rotary drum 22 will separate from the tacks any object so large as not to pass through the comparatively small openings 24, and it is further 40 to be noted that the screen 34 supplements the action of the drum in insuring a uniform distribution of the fastenings to the assorting stations 2. The foreign material separated from the tacks is delivered from 45 the machine by a chute 36 to which it passes through the open delivery ends of the drum 22 and screen 34 and by which it is conveyed to a receptacle 37.

The tacks as they fall from the drum 22 50 are conducted to the assorting stations 2 by means now to be described. Such means comprises oppositely inclined slides 38 formed to present alternating ridges 39 and channels 40 (Fig. 1), the latter being slotted 55 to an extent greater than the diameter of the shanks of the tacks but less than the diameter of the tack heads so that the tacks as they fall from the drum 22 on the slides group themselves in the channels 40 supported by their heads from the walls of the slots. As clearly appears from the drawings (Fig. 60 3), the slides 38 are arranged in the form of an inverted V the apex of which is positioned in the vertical plane of the axis of the drum 22. There is thus provided two

series of channels extending lengthwise of the drum 22 and arranged one at each side of the vertical plane of the axis of the drum so that not only are the tacks distributed uniformly to the individual channels of each 70 series, but they are also delivered uniformly to the channels of the different series. The slide 38 at the left (Fig. 3) is of like construction to that at the right and the assorting mechanism and other parts on one 75 side of the machine are similar to those on the other side. Consequently, a description of the parts on one side of the machine will suffice for both.

To counteract the tendency of the tacks 80 to group themselves in the channels 40 of the slides 38 with their heads riding on each other and to arrange the tacks properly in the channels, I provide a picker 42 operatively associated with each of the channels 85 40 and acting to engage the head or other portion of any tack which by reason of riding on the head of a preceding tack or for other reason is elevated to a greater extent from the slot of the channel than are the 90 tacks which are properly located in the channel. The pickers 42 are mounted in collars 43 secured on a rotating shaft 44 extending from one end to the other of the machine and each is arranged to yield relatively to its 95 collar 43 by means of a spring 46 interposed between an enlarged portion of the picker 42 and the bottom of the recess in the collar which receives the picker. The frame of the machine is curved outwardly at 48 to provide 100 a space in which the picker may be operated. The channels 40 of the slides 38 constitute raceways which convey the tacks downwardly from the drum 22 toward the assorting stations 2.

The tacks pass down the channels 40 to the assorting stations 2 with which are associated means for selecting the tacks according to their lengths and means for positioning the tacks relatively to the selecting means. The 110 means for positioning the tacks comprises a tack carrier 50 formed with a notch 52 of a size to receive a single tack. In order that the selecting means may be caused to remove the tacks from the tack carrier at different 115 points determined by their lengths, means are provided for effecting change in the relative spacing of the tack carrier and the path of movement of the selecting means. Such change may be variously effected but in the 120 embodiment of the invention herein illustrated I have chosen to construct the selecting means in the form of a bar 60 extended transversely of the direction of movement of the tacks in the channels 40 and parallel to 125 the tack carrier 50 and provided with unequally projecting selecting portions 62 and 64 aligned respectively with selecting locations 54 and 56 and to move the carrier 50 so as to carry the notch 52 from a receiving 130

location in alignment with the channel 40 of the raceway to selecting locations 54 and 56 to present the tack suspended by its head from the notch in operative relation to the 5 selecting means.

The selecting bar 60 is operated in a fixed path transversely of the direction of movement of the tack carrier by rotation of the shaft 51 by which it is carried. The path 10 of movement of the selecting means manifestly is nearer the tack carrier 50 in the direction of the lengths of the tacks dependent from the tack carrier at the selecting location 56 which is aligned with the longer 15 projection 64 of the bar 60 than at the selecting location 54 which is aligned with the shorter projection 62 of the bar 60. When, therefore, the tack carrier 50 is moved so as to carry the notch 52 from selecting location 20 54 to the selecting location 56, the notch 52 which positions the tack relatively to the selecting bar 60 is caused to approach the path of movement of the selecting bar in the direction of the length of the tack. The projection 25 62 of the selecting bar is spaced from the upper surface of the tack carrier 50 at the selecting location 54 by a distance less than the length of the longer tacks but greater than the length of the shorter tacks, 30 the operation of the tack carrier 50 and the bar 60 being so timed that the bar is moved by the carrier in the direction indicated by the arrow (Fig. 3), that is, from the open side of the notch 52 toward its closed side, 35 at the time when the notch 52 arrives at the selecting location 54. From the foregoing it will be understood that if the tack in the notch 52 of the carrier 50 is a long one, its point will be engaged by the projection 62 40 of the bar 60 and it will be pushed from the carrier. If, however, the tack is a short one it will not be engaged by the projection 62 of the bar but will be conveyed by the carrier to the selecting location 56 while the shaft 51 45 is completing a revolution into position to be engaged by the projection 64 of the bar 60 when it is again moved past the tack carrier 50, the projection 64 of the bar being spaced from the carrier 50 by a distance less 50 than the length of the shortest tacks being operated upon and operating to remove from the tack carrier any tacks which are not discharged therefrom at the selecting location 54. The bar 60 is formed with an extreme 55 depression 63 in the vertical plane of the channel 40 which insures that the tacks in the raceway will not be struck by the selecting bar in its movement.

Both the tack carrier 50 and the tack selecting bar 60 are preferably and as herein illustrated extended transversely of the channels 40 from end to end of the machine and both of such members are operatively related to all of the channels. Each of 65 said members may be said to comprise a

plurality of like colligate sections one of which is associated with each of the assorting stations 2. The bar 60 is thus formed with alternating longer and shorter projections 62 and 64. As clearly shown in 70 Fig. 3, the tack carrier is slidably mounted on a brace 65 projecting laterally from the machine frame, and the notches 52 are formed in an angular portion 66 of the carrier extending upwardly in the plane of 75 the raceways.

A plate 67 pivoted to the frame of the machine at 68 overlies the channels 40 at their delivery ends and serves to prevent any of the tacks from being thrown upwardly from the channels 40 or the notches 52 either by engagement of the selecting bar 60 therewith or otherwise.

Preferably, the long tacks removed from the tack carrier 50 at the selecting locations 80 54 are collected in a common receptacle which should manifestly be separate from that in which are collected the shorter tacks removed from the carrier at selecting locations 56. To this end the tacks as they are 85 discharged from the presenting means are caused to fall into hoppers 70 which are alternately formed with floors 72 arranged to direct the tacks into a receptacle 74 and with floors 76 constructed to direct the tacks into 90 a receptacle 78 constructed as a part of or located adjacent to the receptacle 74.

The operating means for the machine is as follows. Carried by the shaft 51 on the right hand side of the machine (Fig. 1) are 100 tight and loose pulleys designated together by the reference numeral 82, and endless belts 84 and 86 are provided for transmitting the movement of the shaft 51 to the rotary drum 22 and the magazine 4 respectively. On the opposite end of the shaft 51 is mounted a gear 88 meshing with a gear 90 on a stud shaft 92 suitably journaled in the machine frame, and loosely carried by the stud shaft 92 is a cam disk 94 in the periphery of which is formed a cam slot in which engages a follower extending downwardly from the tack carrier 50 whereby the carrier is operated from a position in which the notches 52 are aligned with the channels 40 to and from the selecting locations 56. Movement of the stud shaft 92 is transmitted to a corresponding stud shaft 95 on the opposite side of the machine (Fig. 3) by an endless belt 96 which passes 110 over pulleys on the respective stud shafts. The shafts 44 on which the pickers are mounted are operated by endless belts 97 passing over pulleys carried by the shafts 44 and the stud shafts 92 and 95, respectively. Preferably, and as shown, a yielding connection is provided between the stud shaft 92 and the tack carrier 50, said connection comprising a spring pressed plunger 98 mounted in the cam disk 94 and 115 120 130

adapted to be seated in a recess 100 in the side of the gear 90. With this construction, if, by reason of a tack becoming jammed between the tack carrier 50 and the end of one of the raceways or for other reason an obstruction is interposed to the movement of the tack carrier, the cam disk 94 is permitted to move relatively to the stud shaft 92 and thus prevent breakage of the parts.

- 10 Manifestly, the bar 60 may be formed with a number of selecting portions variously spaced from the tack carrier 50 corresponding to the number of classifications of the tacks which it is desired to make.
- 15 Thus, if it were desired to assort tacks in more than two groups, the selecting portions or projections 62 and 64 of the bar 60 would be replaced by a greater number of selecting portions and the tack carrier would
- 20 be moved to carry its notch 52 from the receiving location to all the selecting locations.

Having described the invention, what I claim as new and desire to secure by Letters Patent of the United States is:

1. A machine of the class described having a plurality of assorting stations, a source of fastening supply, mechanism associated with each of said stations for assorting fastenings in accordance with a physical characteristic of the fastenings, a perforated drum for distributing the fastenings from said source of fastening supply to said assorting stations, and means for turning said drum about its axis.

2. A machine of the class described having a plurality of assorting stations, a source of fastening supply, mechanism associated with each of said stations for assorting fastenings in accordance with a physical characteristic of the fastenings, a drum constructed to receive fastenings at one of its ends from said source of fastening supply and having openings arranged

40 spirally of its periphery for distributing the fastenings substantially uniformly to said assorting stations.

3. In a machine of the class described, means for separating fastenings from foreign material, such as trash, dirt and the like, and means for assorting the fastenings in accordance with the length of the fastenings.

4. A machine of the class described having a plurality of assorting stations, means for separating fastenings from foreign material such as trash, dirt, and the like, means associated with each of said stations for assorting the fastenings in accordance with

50 a physical characteristic of the fastenings, and means associated with the separating means for distributing the fastenings substantially uniformly to the assorting means.

5. In a machine of the class described, means for separating fastenings from for-

50 eign material such as trash, dirt, and the like comprising pneumatic means for separating the light trash from the fastenings and screening means for separating the heavier dirt and the like from the fastenings and means for assorting the fastenings in accordance with the length of the fastenings.

6. In a machine of the class described, means for operating on fastenings, a chute 75 for conducting fastenings to the operating means, means for supplying fastenings to said chute comprising a cylindrical magazine having a reticulated periphery through which fine dust may pass and provided 80 with members constructed to elevate the material in the magazine to facilitate the discharge of the material from the magazine upon said chute, and pneumatic means for withdrawing light trash from the magazine. 85

7. In a machine of the class described, a screen, a drum for delivering material to said screen constructed to distribute the material substantially uniformly from one end of the screen to the other, and means 90 for turning the drum about its axis.

8. In a machine of the class described, a cylindrical screen, a drum enclosed by said screen and connected thereto for rotation therewith and having a single row of openings arranged spirally of its periphery with substantially one half or more of each opening disposed on the side of a plane at right angles to the axis of the drum and passing through the adjacent end of a contiguous 95 opening opposite from said contiguous opening so as to distribute material substantially uniformly from end to end of the screen, and means for rotating the drum and screen.

9. In a machine of the class described, a frame, a cylindrical screen, disks journaled in said frame and connected to the ends of said screen, a drum connected at its ends to said disks interiorly of said screen for rotation with said screen, and having openings arranged in a single row spirally of its periphery with substantially one half or more of each opening disposed on the side of a plane at right angles to the axis of 115 the drum and passing through the adjacent end of a contiguous opening opposite from said contiguous opening so as to distribute material substantially uniformly from end to end of the screen.

10. A machine of the class described having a plurality of assorting stations and means intermediate between said assorting stations for distributing fastenings substantially uniformly to said assorting stations. 125

11. A machine of the class described having assorting stations arranged on each side of the machine, inclined guides extending upwardly from said assorting stations and meeting in the form of an inverted V and 130

operating to conduct fastenings to said assorting stations, a perforated drum arranged above the guides with its axis substantially in the vertical plane of the apex of the guides and operable to distribute fastenings substantially uniformly to said guides, and means for turning said drum about its axis.

12. A machine of the class described having a plurality of assorting stations arranged on each side of the machine, guides extending upwardly from said assorting stations and meeting in the form of an inverted V and operating to conduct fastenings to said assorting stations, a drum above the guides having its axis substantially in the vertical plane of the apex of the guides, and having openings arranged spirally of its periphery for distributing fastenings substantially uniformly to said guides, and means for turning said drum about its axis.

13. In a machine of the class described, fastening positioning means, selecting means spaced from the positioning means in the direction of the lengths of the fastenings when positioned by the positioning means, means for operating said selecting means to remove the fastenings from the positioning means, and means for effecting a change in the spacing of the path of movement of the selecting means and the positioning means in the direction of the lengths of the fastenings so that the selecting means is caused to remove fastenings of unequal lengths from the positioning means at different times in the cycle of operations of the machine so as to separate such fastenings from each other.

14. In a machine of the class described, power-operated fastening selecting means, means for presenting headed fastenings to said selecting means with their heads spaced from the path of movement of the selecting means in the direction of the lengths of the fastenings by a predetermined distance less than the length of the longest fastenings to be operated upon so that such fastenings are engaged by the selecting means and removed from the presenting means, and means for effecting a closer approach of the path of movement of the selecting means and the presenting means in the direction of the lengths of the fastenings so that shorter fastenings are engaged by the selecting means and discharged from the presenting means.

15. In a machine of the class described, fastening positioning means, means for moving the positioning means, fastening selecting means, and means for operating portions of the selecting means in paths spaced at unequal distances from the path of movement of the positioning means so that one portion of the selecting means operates to remove fastenings of one length from the position-

ing means and a second portion of said selecting means operates to remove fastenings of another length from the positioning means.

16. In a machine of the class described, fastening positioning means, means for moving the positioning means, a member spaced at unequal distances from the path of movement of the positioning means in the direction of the lengths of the fastenings for selecting fastenings from the positioning means in accordance with their lengths, and means for operating said member transversely of the path of movement of the positioning means.

17. In a machine of the class described, a raceway, means at the delivery end of the raceway constructed to receive a headed fastening from the raceway and to support it by its head, means for moving said fastening supporting means in a direction transverse to the path of movement of the fastenings in the raceway, a selector for removing a fastening from the supporting means at a point determined by its length, and means for operating said selector in a direction transverse to the direction of movement of the fastening supporting means.

18. In a machine of the class described, a raceway, a member at the delivery end of the raceway formed with a notch shaped to receive a headed fastening from the raceway, means for moving said member transversely of the raceway with the fastening supported by its head in said notch, and a selector having portions spaced at unequal distances from the path of movement of said member in the direction of the length of the fastening, and means for operating the selector to remove the fastening from said member at a point in the path of movement of said member determined by the length of the fastening.

19. In a machine of the class described, a positioning member having a notch formed to receive a headed fastening and to support it by its head, means for moving said positioning member, a selector having portions spaced from the path of movement of said positioning member in the direction of the length of the fastening by unequal distances, and means for operating said selector in a direction from the open side to the closed side of the notch to remove the fastening from said notch at a point in the path of movement of said member determined by the length of the fastening.

20. In a machine of the class described, a carrier, means for reciprocating said carrier from a fastening receiving location toward and from a plurality of selecting locations, means for delivering fastenings to the carrier at the receiving location, means at one of said selecting locations for removing fastenings of one length from the carrier, and

means at another of said selecting locations for removing fastenings of another length from the carrier.

21. In a machine of the class described, a plurality of fastening guides arranged in substantially parallel relation and adapted for operation on headed fastenings having elongated shanks, and means extending transversely of said guides and constructed to 10 suspend the fastenings by their heads and assort them in accordance with a physical characteristic thereof.

22. A machine of the class described having fastening assorting stations, a notched member extending in co-operative relation with a plurality of said stations for receiving the fastenings and suspending them by their heads, and means for sorting the fastenings while so suspended.

23. A machine of the class described having fastening assorting stations, and co-operating assorting members each extending past and in co-operative relation with a plurality of said stations for assorting fastenings in accordance with a physical characteristic of the fastenings.

24. A machine of the class described having fastening assorting stations and means for assorting fastenings in accordance with a physical characteristic of the fastenings comprising a rotary tack selecting member composed of a plurality of like sections arranged each in operative relative to an assorting station.

25. A machine of the class described having fastening assorting stations, means for delivering fastenings to said stations, fastening selecting means extending in operative relation with a plurality of said assorting stations, means associated with each of said assorting stations for presenting fastenings to said selecting means, and means for effecting a successively closer approach of the presenting means and the selecting means in the direction of the lengths of the fastenings so that the selecting means operates to remove first longer and then shorter fastenings from the presenting means.

26. A machine of the class described having fastening assorting stations, fastening selecting means extending in operative relation with a plurality of said assorting stations, means co-operating with a plurality of said assorting stations for presenting fastenings to said selecting means, means for operating the selecting means to remove fastenings from the presenting means, and means for effecting change in the relative spacing of the presenting means and the path of movement of the selecting means in the direction of the lengths of the fastenings so that the selecting means operates to remove the fastenings from the presenting means in accordance with their lengths.

27. In a machine of the class described, a

plurality of fastening guides, a member extending across the delivery ends of the guides and provided with notches adapted to be aligned with the guides and each formed to receive a single fastening from its respective guide, and means co-acting with said member to remove the fastenings from the member at points dependent upon a physical characteristic of the fastenings.

28. In a machine of the class described, a plurality of fastening guides, a member extending across the delivery ends of the guides and provided with notches adapted to be aligned with the guides and each formed to receive a single fastening from its respective guide, means comprising a yielding connection for moving said member transversely of the guides, and means co-acting with said member to remove the fastenings from the member at points dependent upon a physical characteristic of the fastenings.

29. In a machine of the class described, a plurality of raceways, a member extending across the delivery ends of the raceways and provided with notches adapted to be aligned with the slots of the raceways and each formed to receive a single fastening from a raceway, a bar extending transversely of the raceways below said member and having alternating shorter and longer projections, and means for moving said member longitudinally of said bar to align the fastenings successively with the shorter and longer projections of said bar.

30. In a machine of the class described, a plurality of raceways, a carrier extending across the delivery ends of the raceways and provided with notches adapted to be aligned with the slots of the raceways and each formed to receive a single fastening from a raceway, a bar extending transversely of the raceways below said member and having alternating shorter and longer projections, means for moving said member longitudinally of said bar to align the tacks successively with the shorter and longer projections of the bar, and means for moving said bar in a direction transverse to the movement of said member to remove from said member first fastenings which project toward said bar sufficiently to be engaged by the shorter projection of the bar in its movement and then to remove shorter fastenings from said bar by the engagement of the longer projection of the bar with said fastenings.

31. In a machine of the class described, a plurality of raceways, a carrier extending across the delivery ends of the raceways and provided with notches adapted to be aligned with the slots of the raceways and each formed to receive a single fastening from one of the raceways, a bar extending transversely of the raceways in a substantially

- parallel relation with said carrier and having alternating shorter and longer projections, means for moving said carrier transversely of the raceways to convey fastenings supported by their heads from the carrier first to points in alignment with shorter projections of the bar and then to points in alignment with longer projections of the bar, and means for operating said bar in a direction transverse to the direction of movement of said carrier and from the open side to the closed side of said notches to remove from the carrier first the fastenings of a length to be engaged by the shorter projections of the bar and then to remove shorter fastenings from said carrier by the engagement of the longer fastenings from said carrier by the engagement of the longer projections of the bar therewith.
32. A machine of the class described, having a plurality of assorting stations, means associated with each of said stations for discharging fastenings at different points in accordance with their lengths, and means for collecting fastenings of one length discharged from the various stations separately from fastenings of a different length.
33. In a machine of the class described, a plurality of raceways, a carrier extending across the delivery ends of the raceways and provided with notches adapted to be aligned with the slots of the raceways and each formed to receive a single fastening from one of the raceways, a bar extending transversely of the raceways in substantially parallel relation with said carrier and having alternating shorter and longer projections, means for moving said carrier transversely of the raceways to convey fastenings supported by their heads from the carrier first to a point in alignment with shorter projections of the bar and then to a point in alignment with longer projections of the bar, means for operating said bar in a direction transverse to the direction of movement of said carrier and from the open side to the closed side of said notches to remove from the carrier first the fastenings of a length to be engaged by the shorter projections of the bar and then to remove shorter fastenings from said carrier by the engagement of longer projections of the bar therewith, and means for collecting the fastenings removed from the carrier by the shorter projections of the bar separately from those removed by the longer projections of the bar.
34. In a machine of the class described, a plurality of raceways, mechanism for supplying fastenings to the raceways, and a rotary member associated with the raceways for assorting the fastenings in accordance with their lengths.
35. In a machine of the class described, rotary means for selecting fastenings according to their lengths, means for operating the

selecting means, and means separate from the selecting means for moving the fastenings longitudinally of the selecting means for operation thereon by the selecting means.

36. In a machine of the class described, rotary means for selecting fastenings according to their lengths, means for operating the selecting means, means for supporting fastenings in position for operation thereon by the selecting means, and means for moving the supporting means longitudinally of the selecting means in timed relation thereto.

37. In a machine of the class described, means for selecting fastenings according to their lengths, means for operating the selecting means, means for receiving and supporting fastenings, and means for reciprocating the supporting means to convey fastenings from fastening receiving position into position for operation thereon by the selecting means and to return the supporting means to fastening receiving position.

38. In a machine of the class described, rotary means for selecting fastenings according to their lengths and means for supporting the fastenings in position for operation thereon by the selecting means.

39. In a machine of the class described, rotary means for selecting fastenings according to their lengths, means for supporting the fastenings in position for operation thereon by the selecting means, and means for reciprocating the supporting means.

40. In a machine of the class described, a selector having portions of different degrees of projection, and means for presenting a fastening first in the plane of movement of a portion of the selector having one degree of projection and then in the plane of movement of a portion of the selector having a different degree of projection.

41. In a machine of the class described, a member provided with a notch to receive a headed fastening, means for removing a fastening from said notch, a hopper disposed beneath said member, and means for preventing upward movement of the fastening when removed from said notch thereby to insure the proper discharge of the fastening into said hopper.

42. In a machine of the class described, mechanism formed to provide a plurality of spaced notches to receive fastenings, hoppers disposed beneath said notches, means for removing fastenings from said notches, and a member for preventing upward movement of the fastenings when removed from said notches thereby to insure the proper discharge of the fastenings into said hopper.

43. In a machine of the class described, mechanism for receiving and supporting a plurality of fastenings in spaced relation to each other, movable means for pushing fastenings of one length from said mechanism and delivering them into one receptacle, and

means for delivering the remainder of the fastenings into another receptacle.

44. In a machine of the class described, mechanism for receiving and supporting a plurality of fastenings in spaced relation to each other, movable means for pushing fastenings of one length from said mechanism

and delivering them into one receptacle, and means for delivering fastenings of another length from said mechanism into another receptacle. 10

In testimony whereof I have signed my name to this specification.

ROBERT H. LAWSON.
